ATTORNEY

UNITED STATES PATENT OFFICE

ALEXANDRE GIMONET, OF ARROCHARD, NEW YORK

LIP STICK HOLDER

Application filed September 27, 1929. Serial No. 395,619.

This invention relates to cosmetic holders and has especial relation to a holder that is provided with what may be termed a permanently pointed lip stick, the present invention being an improvement upon the invention disclosed in my application, Serial Number 371,617, filed by me June 17, 1929.

Like the invention disclosed in the application mentioned, the present invention has for an object the provision of a holder with which various kinds of liquid cosmetics may be used, such as lip and other rouge, liquid powder, liquid eye-lash cream, perfume, shaving cream, tooth paste and various other creams and cosmetics, so that the latter may be kept in proper and convenient condition for use.

In addition, the present invention aims to improve and simplify the construction of the invention disclosed in the mentioned application in such a way as to prevent the liquid contents of the container from seeping out and discoloring the fingers or apparel of the user, as well as to provide a holder whereby the cosmetic may be easily and accurately applied.

With the above and other objects in view, the invention further includes the following novel features and details of construction, to be hereinafter more fully described, illustrated in the accompanying drawings and pointed out in the appended claims.

In the drawings:—

Figure 1 is a sectional view of the holder with parts in elevation.

Figure 2 is a longitudinal sectional view of the cap removed.

Figure 3 is a sectional view of the head or discharge end of the container.

Figure 4 is an elevation of the compressible container per se.

Figure 5 is a perspective view of the push button spring.

Figure 6 is an inner plan view of the head cover.

Figure 7 is a longitudinal sectional view showing a modified form of container.

Figure 8 is an end view of the container shown in Figure 7.

Referring to the drawings in detail where-

in like characters of reference denote corresponding parts, the reference character 10 indicates a holder which is open at one end and provided with an externally threaded neck 11. The opposite end of the holder is provided with a tapered opening 12 which is adapted to receive a tapered button 13.

The button 13 is adapted to engage the inner end of a rubber or other compressible container 14 and for this purpose, the inner face of the button is preferably round. The button is movably held in place by means of a spring 15. One end 16 of this spring is engaged in a diametrically disposed opening 17 provided in the button 13, while the other end of the spring is engaged within a groove 18 provided in the wall of the tapered opening 12.

The container 14 is provided near its outer end with an annular shoulder 19 which engages over the edge of the neck 11 of the holder. This end of the container is also provided with an opening 20 which receives the restricted neck 21 of a head 22.

This head is provided with a central opening or passage 23 and with slits 24 which extend inward from the outer pointed end of the head, and these slits have their outer edges flared as shown at 25.

The container is adapted to contain a liquid cosmetic, such as lip rouge, and pressure upon the button 13 will compress the walls of the container 14 and force a portion of its contents outward through the passage 23 and the slits 24. As the outer or discharge end 25 of the head 22 is pointed, the majority of the discharged liquid will be at this pointed end, so that a relatively broad pencil-like stripe or mark may be made which is especially adapted for the application of rouge to the lips.

The container is designed to be used for creams or semi-liquid pastes of various consistencies, and these pastes or creams are forced outward through the openings 24 and 25 through a fabric or other porous cover 26 which is shaped to fit the discharge end or head 22. This cover 26 is clamped upon a shoulder 27 provided upon an annular flange 28 which extends circumferentially of the

head. For this purpose there is provided a flanged ring 29 which removably engages the neck 11 and serves both to clamp the cover upon the head and to secure the head and container within the holder.

A cap 30 is removably mounted upon the discharge end of the holder.

If desired, the container and head may be formed of a single rubber unit as shown at 10 31 in Figure 7 of the drawings. This unit has its outer pointed end 32 provided with discharge slits 33, while an opening or passage 34 extends centrally through the head.

The invention is susceptible of various 15 changes in its form, proportions and minor details of construction and the right is herein reserved to make such changes as properly fall within the scope of the appended claims.

Having described the invention what is 20 claimed is:—

1. In a toilet accessory, a holder open at one end, a compressible container within the holder, a pointed discharge end for the container, said end extending through the holder, means to removably secure the container within the holder, and a movably mounted finger-piece extending into the holder in contact with the container to compress the latter and eject its contents through the discharge 25 end.

2. In a toilet accessory, a holder open at one end, a compressible container within the holder, a pointed discharge end for the container, said end extending through the holder, a porous cover for the discharge end of the container, combined means to retain the cover in position and secure the container within the holder, and a movably mounted finger-piece extending into the holder in contact with the container to compress the latter and eject its contents through the discharge 30 end.

3. In a toilet accessory, a holder open at one end, a compressible container within the holder, a pointed discharge end for the container, said end extending through the holder and said container having an opening in its outer end, a pointed head detachably engaged with the container and having restricted openings for the passage of the contents of the container, a pressure button movably mounted in the holder and engaging the container to compress the latter and discharge its contents, a porous cover removably positioned 45 over the openings of the pointed head, means to retain the cover upon the head and the container within the holder, and a removable cap for the holder.

4. In a toilet accessory, a holder open at 60 one end, a compressible container within the holder, a pointed discharge end for the container, said end extending through the holder and said container having an opening in its outer end, a pointed head detachably engaged 65 with the container and having restricted

openings for the passage of the contents of the container, a pressure button movably mounted in the holder and engaging the container to compress the latter and discharge its contents, a porous cover removably positioned over the openings of the pointed head, a combined cover and head retaining ring detachably secured to the holder, and a removable cap for the holder.

5. A cosmetic dispensing device comprising a holder having a bore extending through each end and tapered toward one end to provide a button seat, a collapsible container in the holder, a discharge nozzle carried by the holder and in communication with the container, a tapering button engaging the container and limited in its outward movement of the holder by the seat, and yieldable means connecting the button to the holder.

6. A cosmetic dispensing device comprising a holder having a bore and extending through each end and tapered toward one end to provide a button seat, a collapsible container in the holder, a discharge nozzle carried by the holder and in communication with the container, a tapering button engaging the container and limited in its outward movement of the holder by the seat, said holder having a groove in the walls of the seat, and a tension member secured to the button and seated in the groove to yieldably connect the button to said holder.

In testimony whereof I affix my signature.
ALEXANDRE GIMONET.
